UNITED STATES PATENT OFFICE.

WILLIAM GEVEKE, OF NEW YORK, N. Y.

PROCESS FOR ECONOMIC STEAM PRODUCTION IN CANE-SUGAR FACTORIES.

1,258,889.

Specification of Letters Patent. Patented Mar. 12, 1918.

Application filed July 3, 1917. Serial No. 178,345½.

To all whom it may concern:

Be it known that I, WILLIAM GEVEKE, a subject of the Queen of Holland, a resident of New York, in the county of New York 5 and State of New York, have invented certain new and useful Processes for Economic Steam Production in Cane-Sugar Factories, of which the following is a specification.

My invention relates to a process of 10 paring bagasse for burning in furnaces, such for example as the furnaces of the steam boilers of sugar mills.

As is well known, bagasse is the term applied to the crushed and broken sugar cane, 15 after the expression therefrom of sugar juice by the cane crushers. Such bagasse commonly contains a large proportion of moisture—this proportion of moisture varying, however, greatly, according to various 20 conditions.

Prof. A. Guell, in a recent paper read before the Louisiana Sugar Planters Association, stated that Louisiana bagasse contains from 40 to 65 per cent. of moisture, 25 and that it is this moisture, more than anything else, that stands in the way of more successful bagasse burning. Charles H. O'Rourke, in a recent paper read before the same association, gives, on the authority of 30 Mr. W. H. Rainer, the B. T. U. value of bagasse ranging from 60 per cent. moisture to 0 per cent. moisture, the B. T. U. value at 60 per cent. being 2599 and at 0 per cent. being 8360.

Because of the very low thermal value of bagasse in the moist condition in which it comes from the crushers, steam drying of bagasse, preparatory to feeding it to the furnaces, has been used to a considerable 40 extent, notwithstanding that it is well known that such steam drying is in itself quite expensive. In fact, Mr. O'Rourke, in his said paper, advises the discontinuance of the burning of bagasse altogether, and 45 recommends instead that it be used for cattle feed.

In the gathering of the sugar cane in the field, the leaves are usually stripped from the stalk and the stalk or cane only is carried to the crusher mills and then, after conversion of that cane into bagasse, the bagasse is carried by suitable conveyers, with or without intermediate steam drying, to the furnaces, and burned. Owing to the 55 difficulties in generating steam in consid-

erable quantities from the bagasse, due to the low fuel value of the latter in its ordinary moist condition, it has been proposed, and to some extent attempted, to burn the leaves themselves in one or more boilers of 60 a boiler battery, steam from the boilers fed with bagasse being mingled with steam from the boilers fed with cane leaves. But the cane leaves themselves do not form a desirable fuel. Being very loose, and dry, 65 they cannot be fed into a furnace so as to supply fuel in proper volume; and at best they make a very hot but fluctuating and irregular fire.

My invention consists in raising the caloric value of bagasse in its ordinary wet condition as it emerges from the crusher mills, by mixing intimately therewith in suitable proportion loose, dry fuel, preferably plant leaves, and still more preferably 75 the leaves of the sugar cane itself. If the plant leaves so mixed with the bagasse be large leaves, such as the ordinary cane leaves, they are preferably cut or chopped into small pieces, before being fed into mixture with the bagasse. Such naturally dried material has in itself high calorific value; and moreover, because of its loose nature, it tends to open up the mass of bagasse, facilitating the passage of air therethrough 80 and facilitating greatly the propagation of combustion through the mass of moist bagasse. Furthermore, this mixture of bagasse and leaves can be carried more readily than the bagasse itself, by the usual 85 bagasse conveyers, and can be fed into the boiler furnaces more readily than can the bagasse alone. In the case of boilers in battery, all of the boilers of the battery may be fed by this mixture of bagasse and 90 leaves; *i. e.*, all of the boilers may be fed with the same fuel, so that, other things being equal, all the boilers of the battery will steam alike; an extremely important 95 condition in the case of boilers operated in 100 battery.

As will be judged from the foregoing, the object of my invention is to facilitate the burning of wet vegetable material, particularly bagasse.

In the accompanying drawings I illustrate apparatus adapted for carrying out the process above outlined. In the said drawings Figure 1 is a side view and Fig. 2 105 a top view of apparatus for crushing cane 110

into bagasse, for cutting cane leaves and mixing them with the bagasse, and for conveying the mixture to steam boiler furnaces.

In these drawings, 1 designates an ordinary cane crusher mill, or the final mill of a series of such crushers, and 2 designates a chute down which the bagasse from such mill 1 passes. 3 designates, more or less diagrammatically, a leaf-cutter, which may be of any desired construction, and 4 designates a chute by which the cut leaves are deposited in admixture with the bagasse passing down the chute 2.

5 designates an ordinary bagasse conveyor, usually of the chain-link type, whereby the mixture of bagasse and leaves is carried from the pile formed in front of the chutes 2 and 4, to the downtakes 6 in front of the boiler furnaces 7.

20 In carrying out my process, the leaves are stripped from the cane in the field, as is customary, and the cane is carried to the crushers while the leaves are collected and carried to the cutter 3. These leaves are 25 already well dried before they are stripped from the cane; hence they require no drying, either on the ground or elsewhere. The mixture of bagasse and leaves, formed by the joint action of the crusher mills 1 and 30 leaf cutter 3, is conveyed, as already de-

scribed, to the boiler furnaces and the mixture burned therein. As already explained, the dry leaves not only add calorific value, but open up the mass of bagasse so as to facilitate the passage of air and flame gases therethrough, and also facilitate the propagation of flame through the mass, tending to prevent the formation of "holes" in the fire bed as well as the formation of dead spots in the fire bed, and to produce uniform combustion of the mass of fuel.

What I claim is:

1. The herein described method of preparing bagasse for combustion in boiler furnaces and the like, which consists in mixing intimately with such bagasse dry vegetable material, particularly dry leaves.

2. The herein described method of preparing bagasse for combustion in boiler furnaces and the like, which consists in cutting dry cane leaves and intimately mixing the cut leaves with the bagasse.

In testimony whereof I have signed this specification in the presence of two subscribing witnesses.

WILLIAM GEVEKE.
